ROBERT EMERSON BROWN, OF OLEAN, NEW YORK.

SAFETY-RAZOR-BLADE HOLDER.

1,120,442.

Specification of Letters Patent.

Patented Dec. 8, 1914.

Application filed May 6, 1914. Serial No. 836,657.

To all whom it may concern:

Be it known that I, ROBERT EMERSON BROWN, a citizen of the United States, and a resident of Olean, in the county of Cattaraugus and State of New York, have invented a new and Improved Safety-Razor-Blade Holder, of which the following is a full, clear, and exact description.

My invention relates to safety razor blade holders—that is, to devices used for holding a safety razor blade during the operation of honing or strapping the blade.

As is well understood in this art, safety razor blades, because of their form and sharpness, are exceedingly difficult to handle without danger of an accident, and the difficulty of handling the blade is increased because of the fact that the honing and strapping of the blade is done quickly.

I seek to produce a safety razor blade holder in which the razor blade can be quickly and positively clamped, and when once in position is not easily disturbed. Moreover, I seek to produce a device of this character in which blades of all styles—that is to say, with or without backs, and having any reasonable width or any thickness likely to be employed, may be held. I further seek to produce a safety razor blade holder in which the blade can be secured without undue precaution being taken and without requiring greater care than the average person is likely to use. I further seek to produce a blade holder which, when used for purposes of honing or strapping the blade, will necessarily present the blade at a suitable angle to the strap or hone. In addition, I seek to accomplish other results looking toward improving the general efficiency of devices of this character.

Reference is made to the accompanying drawings forming part of this specification and in which like letters indicate like parts.

Figure 1 is a view, partly in plan and partly in section, showing my improved safety razor blade holder; Fig. 2 is a side elevation of the same; Fig. 3 is a section on the line 3—3 of Fig. 2, looking in the direction of the arrow; Fig. 4 is a fragmentary view, partly in bottom plan and partly in section, showing the device with the movable parts occupying certain predetermined positions; Fig. 5 is a view somewhat similar to Fig. 4 but showing the movable parts as occupying different positions from those in-

dicated in said figure; Fig. 6 is a detail view, showing in side elevation a portion of one of the side bars; Fig. 7 is a perspective view showing a protector used for encircling the blade while carried in the holder but not in use for any purpose; and Fig. 8 is a section on the line 8—8 of Fig. 2.

Two side bars are shown at 8, 9. The bar 8 is provided with two slots 10, 11. Two guide pins are shown at 12, 13 and extend through different portions of the bar 9, to which they are rigidly secured. The guide pin 12 is provided with an enlarged portion 14 and with a flat head 15, the enlarged portion 14 extending through the slot 10 of the bar 8. Another guide pin 16 is carried by a thumb lever 14^a and extends through the slot 11. Another guide pin 18 is carried by the bar 8 and is provided with an enlarged portion 19 and with a flat head 20, the portion 19 extending through a slot 21 in the bar 9. The slot 11 of the side bar 8 has the form indicated in Fig. 6—that is to say, it is substantially L-shaped. The parts are so arranged that with the thumb lever 14^a occupying the position indicated in full lines in Fig. 2, the side bars 8, 9 are in registry at the left of Fig. 1. If the lever 14^a be swung outwardly a little, the side bars are not moved relatively to each other until the lever moves out far enough to allow a finger to be inserted beneath it. By this time it begins to cause each of the bars 8, 9 to move relatively to the other. The lever being moved into the position indicated by dotted lines in Fig. 2, the bars 8, 9 are considerably out of registry at their ends to the left, according to Figs. 2 and 5.

The side bars 8, 9, are provided with portions 22, 23, which at their upper edges are bent outwardly, or spaced apart, as indicated in Fig. 1. Because of their form, the portions 22, 23 (with the wedge-shaped space between them) are virtually thicker than the end portions of the bars. The slot 10 extends into the outwardly-bent portion 22, and the slot 21 extends into the outwardly-bent portion 23. The upper edges at the ends of the portions 22, 23, are adapted to meet together, but the lower edges do not meet together. The side bars are also provided with extending lips 24, 25. Whenever the bar 8 is moved to the left and the bar 9 is moved to the right, according to Fig. 2, the bars 8, 9 are forced bodily to-

gether in consequence of the action of the guide pins 12, 18, in the slots 10, 21, and the lower edges are moved toward each other and the lips 24, 25, are either pressed tightly together or pressed against opposite faces of a blade inserted between them, as hereinafter described. The lip 25 has its ends bent slightly as indicated at 26, and the lip 24 has its ends similarly bent at 27. The parts are so arranged that when the lips 24, 25, are moved relatively to each other in the general direction of their length, so as to be displaced relatively to each other as indicated in Fig. 5, and at the same time the bars 8, 9, are loosened relatively to each other by action of the guide pins 12 and 18 in the slots 10 and 21, the bent portion 26 of the lip 25 rides upon the adjacent flat portion of the lip 24, and similarly the bent portion 27 of this lip rides upon the adjacent flat portion of the lip 25. The lips 24, 25 are thus forced apart as may be understood from Fig. 5. When, however, the side bars are moved into the position indicated in Figs. 1 and 4, and as indicated by full lines in Fig. 2, the bent portions 26 engage the bent portions 27 and the lips 24, 25 are now pressed tightly together by action of the pins 12 and 18, as above described.

30 A razor blade is shown at 28. In order to insert it in the holder, the latter is brought into the position indicated in Fig. 5, the lips 24, 25, however, being in their lowermost positions, as indicated by dotted lines in Fig. 2. A gage box 29 is next placed upon a table or the like, and the device is placed upon it, as indicated in Fig. 2, so that the lips 24, 25 extend nearly but not quite into engagement with the surface upon which the gage box rests. The blade 28 is next dropped in between the portions 22, 23, as may be understood from Fig. 3. Next the lever 14^a is moved into the position indicated by full lines in Figs. 1 and 2. This causes the lips 24, 25 to press against opposite sides of the blade and securely grip the same. The holder may now be raised out of engagement with the gage box 29 and is ready for use.

50 In order to hone or strap the blade, the holder carrying the blade is wielded in much the same manner as an old fashioned razor. The proportions of the bars, and particularly of the portions 23, 24, is such that the blade necessarily assumes the proper angle relatively to the surface upon which it is to be honed or strapped.

I do not limit myself to the precise construction shown, as variations may be made therefrom without departing from the spirit of my invention.

Having thus described my invention, I claim as new and desire to secure by Letters Patent:—

65 1. In a safety razor blade holder, the

combination of a pair of side bars movable relatively to each other in the general direction of their common length, each of said bars being provided with a lip having a bent portion at its end and a flat portion merging into said bent portion, the bent portion of one lip being adapted to engage either the bent portion or a flat portion of the other lip, depending upon the relative position occupied by the two side bars, means 70 for shifting one of said side bars endwise relatively to the other in order to force said lips toward each other, for the purpose of gripping a razor blade therebetween, and mechanism controllable by the endwise 75 movements of the bars for clamping the bars together.

2. A safety razor blade holder comprising a pair of side bars each provided with a portion extending laterally therefrom and 80 formed into a lip, said lip having end portions bent in different directions to space said lips slightly apart when said side bars are shifted endwise relatively to each other, lever mechanism connected with said side 85 bars for shifting one of said side bars endwise in relation to the other, in order to grip a razor blade between said lips, and means for clamping said side bars together.

3. In a safety razor blade holder, the 90 combination of a pair of side bars provided with laterally bent portions and further provided with straight portions and with slots located partly within said straight portions and partly within said laterally bent 95 portions, guide pins extending through said slots and provided with heads, so that when one of said side bars is moved relatively to the other said guide pins tend to squeeze said side bars together, and a razor blade to 100 be gripped between said outwardly extending portions when said side bars are thus squeezed together.

4. In a safety razor blade holder, the 105 combination of a pair of side bars provided with end portions disposed parallel with each other and further provided with portions bent outwardly and thus spaced apart, said side bars being also provided with lips for holding a razor blade, means controllable 110 by the travel of one of said side bars relatively to the other in the general direction of the length of said side bars for forcing said lips together, and lever mechanism connected with said side bars for moving one 115 of said side bars lengthwise in relation to the other.

5. A device of the character described comprising a pair of side bars provided with lips extending laterally therefrom, said 120 side bars being further provided with means controllable by endwise movement of one of said side bars relatively to the other for pressing said lips toward each other, means 125 controllable at the will of the operator and 130

connected with said side bars for moving one of said side bars in the direction of its length relatively to the other, and a gage box for engaging said side bars, said gage box having a depth greater than the width of said lips in order to facilitate the positioning of a blade in relation to said lips.

In testimony whereof I have signed my name to this specification in the presence of two subscribing witnesses.
